MERCERIZING PROCESS

Filed June 28, 1926

UNITED STATES PATENT OFFICE.

ARNOLD BOSSHARD, OF ARBON, SWITZERLAND.

MERCERIZING PROCESS.

Application filed June 28, 1926, Serial No. 119,137, and in Germany July 3, 1925.

The present invention relates to improvements in chainless mercerizing machines and has for its object to provide a machine of this type with which the desired mercerizing effect may be satisfactorily imparted to fabrics of thin or thick, close or loose quality. This result is due to improvements in the manner in which the steeping, tensioning and stretching, washing and rinsing is carried out.

With the hitherto known manner of mercerizing woven fabrics lye of the same concentration and temperature has been used in different compartments of the steeping apparatus. From a storage tank for the cooled lye the latter is caused to flow simultaneously to the single compartments in such a quantity that a certain surplus quantity flows back into the storage tank, in which the lye is continuously kept at the same concentration and at a constant low temperature so that owing to the excess quantities in the different compartments in which the treatment is effected the concentration and temperature of the lye are constant. It is known that fabrics are only gradually saturated when brought into contact with cold and concentrated lye so that a certain time elapses until a fabric is completely saturated with soda lye. Therefore an impregnation of the fabric cannot occur in the first compartment and the following compartment unless the treatment were prolonged in an inadmissible manner. Therefore one had to be satisfied with a partial saturation in the first compartments and a complete impregnation occurred only in the last compartment of such apparatus. A good and uniform mercerizing effect could not be obtained by working in this known manner.

The method of the present invention overcomes the undesirable features attendant upon incomplete initial impregnation of the fabric. Advantage is taken of the fact that the fabric is easily and readily penetrated by warm lye or other mercerizing liquid, and even more readily by weak or dilute solutions of such liquid. Accordingly the fabric is passed through a series of baths of lye of gradually decreasing temperature and of gradually increasing concentration, whereby the fabric in the initial baths is rapidly and completely impregnated with relatively warm, weak lye so that its subsequent immersion in the cold concentrated liquid results in a very rapid and thorough mercerization.

The present preferred method of so progressively heating and diluting the initial or

preliminary baths of mercerizing liquid comprises passing an endless web of fabric through a series of interconnected tanks of such liquid, the last tank through which the fabric passes being supplied with chilled concentrated liquid, and the foregoing tanks receiving their supply each in turn from the tank through which the fabric next passes. Thus the initial tank through which the fabric passes contains liquid which has been cumulatively warmed and diluted by the successive passages of the preceding fabric, and each successive tank containing liquid correspondingly cooler and less dilute; while the last tank, in which the mercerization is completed, contains fresh, cold and concentrated liquid.

Another feature of the chainless mercerizing machine according to the present invention is the means for effecting the stretching of the fabric.

In the known chainless mercerizing machines, the breadth stretching of the fabric against its shrinkage owing to the preceding saturation with soda lye for the purpose of producing the mercerizing effect is carried out by means of breadth stretching devices which for the most part consist of curved rollers or cylinders ridged on the periphery or provided with helical grooves rising in opposite directions towards both ends, the said rollers or cylinders being arranged transversely to the fabric, straight or in a curve, and one behind the other.

Such breadth stretching devices only to a small extent impart to the fabric a simultaneous longitudinal stretching, which is likewise extremely important for the mercerizing effect, and even the breadth stretching action leaves something to be desired in consequence of the slipperiness of the saturated fabric. For each kind of fabric there is a quite definite degree of adhesion of the fabric to the periphery of the breadth stretching cylinders or rollers. This, however, in the case of a particular construction of the breadth stretching device is only present at any time for one particular kind of fabric which is just especially adapted to this construction, so that the chainless mercerizing machines can as a rule only impart satisfactorily to quite a definite fabric the desired mercerizing effect, while for all other goods of thinner or thicker, closer or looser quality they produce more or less poor results.

With the machine according to the pres-

ent invention the above defect is remedied by interposing between the steeping apparatus and the breadth stretching apparatus for the fabric an adjustable longitudinal tensioning device. The latter renders it possible to adjust accurately the adhesion of the goods to the cylinder or roller peripheries of the spreading apparatus, which is required for the correct spreading action for each kind of fabric, by suitable regulation of the longitudinal tension of the goods, and thereby to obtain in each instance the best action of the stretching apparatus and consequently the best mercerizing effect for the kind of goods in question.

A further feature of the chainless mercerizing machine according to the present invention is the stretching, washing and rinsing apparatus with which the washing liquid is led in a counter-flow to the fabric to be washed so that the liquid which contains the largest percentage of the washed out lye is at the side of the apparatus at which the fabric to be washed enters it, whereby the liquid which flows off at this end is well suited for recovering the lye which it contains.

With known mercerizing machines the lye is removed from the fabric in a breadth holding apparatus the whole of it is arranged in a treatment tank constructed as a washing box in which case the entire breadth holding apparatus lies in the treatment liquid with the material. Further the washing liquid has already been brought into action by spraying the fabric on both sides, the entire breadth holding apparatus being enclosed in a treatment trough. This spraying process has also been employed on the counter-current principle, the treatment trough which receives the treatment liquid being separated into compartments located one behind the other, out of which the used treatment liquid is taken forwardly in series, and the treatment liquid flowing away from the last portion of the stretching apparatus being supplied to the immediately preceding part of the stretching apparatus, and so forth.

With the chainless mercerizing machine forming the subject matter of the present invention the apparatus for washing comprises a chest in which the fabric is subjected to a steam treatment and passes through various compartments in succession in which it is washed; the washing water being sprayed to the fabric after it leaves the chest and flows from one compartment in the chest to the next by means of over-flow crests. In combination with this steam chest a breadth stretching apparatus is provided in which the rollers are submerged in the washing liquid, baffle plates being arranged to provide for a tortuous path of the washing liquid which flows on the counter-current principle towards the end at which the fabric enters the apparatus. The washing liquid is thus

caused to intimately contact with the fabric which moves in the opposite direction so that a very perfect washing effect is obtained.

A constructional example of the subject matter of the present invention is illustrated on the accompanying drawings, in which:

Fig. 1 is a vertical section of the machine along line I—I in Fig. 2, and

Fig. 2 is a plan view of Fig. 1 in which the fabric is partly omitted.

In the drawings the fabric to be treated is shown in Fig. 1 by the thick full line 1. The fabric, which passes through the machine in the direction indicated by the arrows A at the entrance end and B at the exit end, enters first the steeping apparatus composed in the example shown of two units 2 and 3. The fabric is led over a guide roller 4 into a vessel or compartment 5 in which it passes around a guide roller 6 submerged in the mercerizing liquid, i. e. soda lye, contained in the compartment 5; thereupon it passes between a large roller 7 and a squeezing roller 8, whereby the mercerizing liquid is squeezed out, into the next compartment 9 containing lye, around a submerged guide roller 10, over a guide roller 11, between the guide roller 12 and the squeezing roller 8 and from there over a guide roller 13 into the unit 2 of the steeping mechanism. This unit is similarly constructed as the unit 1 and the same reference numerals are applied to its parts as in the case of the unit 1 with the exception of the two compartments which are designated with the numerals 14 and 15.

The rollers of the steeping apparatus are driven from the main shaft 16 by the interposition of the transmission gearings 17, 18 and 19, 20 (Fig. 2) of which the gear wheel 20 is keyed to one end of the shaft 21 of the uppermost roller 12. To the other end of the shaft 21 a gear wheel 22 is fixed which cooperates with a gear wheel 24 fixed on the shaft 25 of the roller 7 by means of the intermediate gear wheel 23. The connection between the train of gear wheels of the unit 1 and the main driving shaft 16 is effected by means of the conical pulleys 26 and 27, belt 28 and counter-shaft 29.

The concentrated and cooled lye is supplied from any source, for instance from a storage tank, by means of the pipe 30 to the compartment 15, from where it flows over the partition wall 31 into the compartment 14, thence through pipe 32 into the compartment 9 and over the partition wall 33 into the compartment 5 from where it is led off by the pipe 34. The highest concentration and the lowest temperature of the lye is thus in the compartment 15; the concentration gradually decreasing and the temperature increasing in the compartments 14, 9 and 5 due to the cumulative heating and diluting effect of the fabric, so that in the latter the soda lye will have the lowest concentration and

the highest temperature. Thereby the novel effect is attained that the fabric is already well saturated with lye in the first compartment as the higher temperature and lower 5 concentration of the lye in this compartment ensures a ready saturation. The lye is squeezed out of the fabric after it has left the first compartment and the fabric is saturated in the next compartment with a more concentrated lye having a lower temperature, which lye is again squeezed out and so on until in the last compartment saturation with lye of the highest concentration and of the lowest temperature is obtained and the mercerizing effect 10 is completed. Obviously the steeping apparatus may comprise more than two units. By this method of gradual mercerization a better mercerizing effect, a considerable saving 15 in concentrated cooled mercerizing liquid and in time is obtained. As the consumption of concentrated, highly cooled lye occurs solely in the last compartment only small quantities of such lye are required so that a saving in the cooling work is obtained.

20 25 Obviously instead of having only one storage tank from which the concentrated and cooled lye is fed to the last compartment of the steeping apparatus and instead of letting the lye flow by gravity into the preceding compartments whereby its concentration and temperature adjusts itself a separate storage tank for each compartment may be provided in which tanks lye of different strength and temperature is stored and led to the respective 30 35 compartment of the steeping apparatus.

After the web of the fabric has left the roller 12 of the unit 2 of the steeping apparatus it is led to an adjustable longitudinal tensioning device 35. The latter comprises two stationary guiding rollers 36 and 37 and a guiding roller 38 rotatably mounted at its ends in guide blocks 39 which are displaceable along guidances 40 provided in the frame of the device 35. The guide blocks are influenced by 40 45 weights 41 connected to the former by pulling organs 42 passing over guide pulleys 43. The web passing over the guiding rollers 36, 38 and 37 is thereby subjected to a longitudinal stretching effect. This stretching effect can be adjusted by adjusting the load 41 according 50 55 to the nature of the fabric and to the nature of the subsequent breadth stretching apparatus in order to attain the desired effect. By the aid of this adjustable longitudinal tensioning apparatus the mercerizing machine admits of being adapted easily and conveniently to any type of fabric so as to attain the best ultimate effect. Obviously the longitudinal tension may be produced by any 60 other means well known per se. The tensioning by means of weights is advantageous inasmuch as it adapts itself automatically during working to the various working conditions and thereby maintains the longitudinal tension, once adjusted uniform during working.

The fabric leaving the longitudinal stretching device passes thereafter to the breadth stretching and washing apparatus. The breadth stretching apparatus illustrated comprises a plurality of curved stretching rollers 70 of the known type which are subdivided in the running direction of the web of fabric into two sets arranged at different heights. The first set comprises five rollers 44 which are in driving connection with each other by 75 the gear wheels 45 provided at their ends and the gear wheels 45 are driven from shafts 46 and 47 provided with gear wheels 48 and 49 respectively which are in mesh with some of the gear wheels 45.

80 The second set of curved stretching rollers comprises eight rollers 50 arranged in a treatment tank 51. The rollers 50 are in operative connection with each other by means of gear wheels 52 and the latter are driven by gear 85 wheels 53 and 54 on the shafts 55 and 56 respectively. The shafts 46, 47, 55 and 56 are rotated from the main driving shaft 16 through the interposition of the conical pulleys 57, 58, belt 59, countershaft 60, chain 90 wheels 61 and chains 62, 63 and 64.

Baffle plates 65 are provided in the treatment tank 51 in order to provide a tortuous path for the washing liquid which is thereby caused to flow in an opposite direction to that 95 in which the fabric moves and in close contact with the latter so that an effective washing is obtained.

The fabric leaving the last of the stretching rollers 50 passes over a guide roller 66 and from there into the steam treatment washing apparatus 67. The latter comprises a set of upper guide rollers 68 and a set of lower guide rollers 69 mounted inside a chest 70 and over which the fabric passes. The lower rollers 100 105 69 are separated from each other by partition walls 71 whereby different compartments 72 are formed, the upper rollers 68 are mounted at the same elevation in the steam space of the chest 70. From the last of the lower 110 rollers 69 the fabric passes between the squeezing rollers 73 and 74, the upper one of which is loaded by the weight 75 through the intermediary of a system of levers 76. 77 denotes a pipe for supplying water for washing purposes which is sprayed on the fabric before it passes between the squeezing rollers, and 78 is a pipe for supplying steam to the chest 70. The rollers 68 are rotated from the counter-shaft 60 by means of the conical pulley 79, 115 belt 81, and belt pulley 80 fixed to the shaft 82 of the roller 68 and a train of chain wheels 83 and chains 84.

The partition walls 71 are of different 120 heights so that the washing liquid which is supplied by the pipe 77 flows from the last compartment 72 over the partition wall 71 into the next compartment and so on until the last compartment from where the liquid enters the treatment tank 51 containing the 130

breadth stretching rollers. Within the tank 51 the washing liquid is caused by the baffle plates 65 to flow in intimate contact with the fabric but in opposite direction to that in 5 which the fabric moves, until the washing liquid is discharged through the pipe 85. The difference in the liquid levels inside the chest 70 and in the treatment tank 51 is caused by the pressure of the steam admitted 10 into the chest 70.

As the washing liquid flows into the apparatus from the pipe 77 at the end at which the fabric leaves the apparatus it is apparent that the washing liquid in the last compartment 15 72 will contain the least portion of the washed out mercerizing liquid. This percentage of mercerizing liquid will gradually increase in the preceding compartment 72 of the chest and the highest percentage will be present at 20 the beginning of the treatment tank 51 where the washing liquid is discharged. The washing effect is sufficiently gradual in order not to impair the mercerizing effect in certain goods.

25 The invention in its broader aspects is not limited to the specific steps set forth nor the specific mechanisms shown and described but departures may be made therefrom within the scope of the accompanying claims without 30 departing from the principles of the invention and without sacrificing its chief advantages.

I claim:

35 1. The method of mercerizing fabrics which consists in subjecting the fabric to a series of baths of mercerizing liquid, of gradually increasing concentrations and gradually decreasing temperatures, squeezing the fabric after each bath, and subjecting the fabric to longitudinal tension.

40 2. The method of mercerizing fabrics which consists in subjecting the fabric to a series of baths of mercerizing liquid of gradually increasing concentrations and gradually decreasing temperatures, squeezing the fabric, subjecting the fabric to longitudinal and transverse stretching, washing the fabric in a combined steam and liquid bath, and rinsing the fabric.

45 3. The method of impregnating fabric with mercerizing liquid which comprises subjecting the fabric to a series of baths of mercerizing liquid of gradually increasing concentration whereby the fabric is rapidly penetrated by the dilute liquid to facilitate the mercerizing action of the concentrated liquid.

50 4. The method of mercerizing a web of fabric which comprises passing the fabric through a series of baths of mercerizing liquid of gradually decreasing temperature and gradually increasing concentration and subjecting the fabric to a longitudinal tension during the steeping process.

55 5. The method of mercerizing fabrics

which comprises subjecting the fabric to a series of mercerizing baths of successively increasing concentration and successively decreasing temperature whereby the fabric is rapidly penetrated by the dilute, warm liquid 70 to facilitate the mercerizing effect of the concentrated, cooler liquid.

6. The method of impregnating fabric with mercerizing liquid which comprises passing the fabric through a counter flowing 75 current of mercerizing liquid from a low temperature source whereby the fabric first encounters warmed and diluted mercerizing liquid and passes through mercerizing liquid of gradually decreasing temperature and 80 gradually increasing concentration.

7. The method of impregnating fabric with mercerizing liquid which comprises passing the fabric through a series of baths of mercerizing liquid, introducing cold concentrated 85 mercerizing liquid into the last bath through which the fabric passes, and directing the liquid from each bath into the preceding one whereby each preceding bath contains liquid of higher temperature and lower 90 concentration than the succeeding.

8. The method of mercerizing a web of fabric which comprises passing the fabric through a series of baths of mercerizing liquid of gradually decreasing temperature and 95 gradually increasing concentration, washing and rinsing the fabric and maintaining the web of fabric under longitudinal and lateral tension until all the excess mercerizing liquid 100 has been washed out of the fabric.

9. The method of mercerizing a web of fabric which comprises passing the fabric through a series of baths of mercerizing liquid of gradually decreasing temperature and 105 gradually increasing concentration, passing the fabric through a counter flowing washing current and maintaining the web of fabric under longitudinal and lateral tension until all the excess mercerizing liquid has been 110 washed out of the fabric.

10. The method of mercerizing fabric which comprises preliminarily immersing the fabric in a bath of mercerizing liquid which has been warmed and diluted by a plurality of prolonged immersions of fabric, then immersing the fabric in mercerizing liquid which has been warmed and diluted to a less degree by shorter contact with fabric, and ultimately immersing the fabric in a fresh bath of cold concentrated mercerizing liquid.

11. The method of impregnating fabric with mercerizing liquid which comprises subjecting the fabric to a bath of mercerizing liquid having a temperature substantially the same as that of the fabric and thereafter subjecting the fabric to baths of mercerizing liquid having successively lower temperatures, whereby the penetration and mercerizing action of the cold liquid is enhanced by 120 125 130

the preliminary impregnation of the warmer liquid.

12. The method of impregnating fabric with mercerizing liquid which comprises passing a web of fabric through a series of communicating baths of mercerizing liquid, progressing the liquid through the baths in a current counter of the movement of the fabric and feeding low-temperature liquid to the last bath through which the fabric passes whereby the fabric initially enters a bath of relatively warm liquid and passes through a series of baths of successively lower temperature.
13. The method of impregnating fabric with mercerizing liquid which comprises subjecting the fabric to a series of baths of mercerizing liquid, the temperature of the first bath being highest and each succeeding bath being

of very slightly lower temperature than the preceding whereby a gradated penetration and mercerization of the fabric is effected.

14. The method of mercerizing fabric which comprises preliminarily immersing the fabric in a bath of mercerizing liquid which has been warmed and diluted by a plurality of prolonged immersions of fabric, then immersing the fabric in mercerizing liquid which has been warmed and diluted to a less degree by shorter contact with fabric, and ultimately immersing the fabric in a fresh bath of cold concentrated mercerizing liquid and squeezing the fabric between the successive baths.

In testimony whereof, I have signed my name to this specification.

ARNOLD BOSSHARD.
